UNITED STATES PATENT OFFICE.

ALBERT ROSENBERG, OF BALTIMORE, MARYLAND.

LOOSE-LEAF BINDER.

1,371,646.

Specification of Letters Patent. Patented Mar. 15, 1921.

Application filed January 2, 1917. Serial No. 140,260.

To all whom it may concern:

Be it known that I, ALBERT ROSENBERG, a citizen of the United States, residing at Baltimore city, in the State of Maryland, 5 have invented a new and useful Improvement in Loose-Leaf Binders, of which the following is a specification.

My invention relates to leaf binders for leaves of books, periodicals, drawings, specifications, manuscripts, and the like; the objects of which are to provide a means for ready access to the leaves when held by my binder; 2nd, to enable the same to be clasped at both ends when out of use; 3rd to permit the leaves to be increased or diminished in numbers at will; 4th, to enable the user to move the front and back of the binder out of way when using the leaves; 5th, to provide a movable across the face of the 15 leaves or cover structures; 6th, to provide means for simultaneously moving the cover structures; 7th, to provide means for simultaneously moving the tension device and the cover structures; 8th, to provide detachable tension device for the outer parts of 20 the leaves.

I attain these objects by the devices illustrated in the accompanying drawings in which—

30 Figure 1 shows my leaf binder attached to a bundle of leaves.

Fig. 2 shows the outer bar of my binder in sectional view.

Fig. 3 shows a sectional view of the nut, 35 or cap with which the pin or post is secured in the leaves.

Fig. 4 illustrates a longitudinal view of the pin or post.

Fig. 5 illustrates a view of a stop to prevent the extensible cover structure from 40 extending beyond a fixed limit.

Fig. 6 illustrates a sectional view of a covered tension device for securing and operating the front and back cover structures 45 of my leaf binder simultaneously.

Fig. 7 is a longitudinal section of parts of the cover structure and its detachable tension device with the end of the latter shown passing through the orifice in the 50 head of the pivot.

Fig. 8 is a sectional view of the tubular pivot.

Fig. 9 is a sectional view of a solid pivot.

Referring to the drawings, the numeral 1 55 designates a series of leaves, on the faces of which both front and back, are attached the

movable across the face of the leaves and adjustable cover structures, enabling the leaf binder to be either increased or diminished in size according to the area of the 60 leaves, by moving the cover structures across the faces of the leaves; or, moved out of way of the user of the book at will; as illustrated on the face of the top sheet or leaf. The binder comprises said adjustable cov- 65 ers having a bar 18 on the front and 11 on the back, all held together by suitable posts and nuts 15, 16, 17; and to these bars are pivoted the movably adjustable parts of the cover structures 23, 7, 9, 20 by the pivots 70 12 and 19, the parts 23, 7, 9, 20 being held together by the pivots 8 and 21.

At the outer end of these movably adjustable parts are pivoted the bars 26 by the pivots 24 and 6 and to the outer ends are 75 detachably secured the springs 4, the tension devices for clamping the loose ends of the leaves and the movable cover structures.

On the adjustable parts of the movable cover structures are arranged suitable stops 80 10 and 22 to limit the extensibility of the movable and adjustable cover structures.

These stops may be placed at any suitable point on my leaf binder or upon the leaves, and stops 10 and 22 are provided with a head 85 22' a body portion 32 having a reduced end 34 and a shoulder 33 the reduced portion 34 being inserted in and secured to the movable parts 9 and 23 of the movable cover structures. 90

The tension device shown in modified form in Fig. 6 may be secured to the movable mated parts 23—7 and 26 of the cover structure by any suitable means such as screwing, riveting, or made detachable by 95 using a hook made by bending the end 36 in a similar manner to the spiral spring end 23 shown in Fig. 7, extending through the orifice 24' of the pivot 24.

This end 36 is made integral with the 100 shoulder 35 of the casing or barrel 4' which covers the spring 4" and in which is inserted the plunger stem provided with a flange 5" operating against the spring 4" held in the casing 4' by the detachable 105 nut 37.

The plunger 5" is flanged at 38 and is secured to the mate of the cover structures by 5'.

In Fig. 4, the post 30 is shown with a 110 round head 29 and a threaded portion 31 at its other end, and is used to secure the ad-

justably movable cover structures to the leaves of the book as well as to bind the leaves of the book together.

In Fig. 3, the nut or cap 15 is shown with 5 a round head 15' and provided with key holes 13 and 14 and a female thread 35.

Fig. 7 shows a hollow or tubular pivot 24 with an orifice, in which to insert the end 25 of spring, 4, while the lower portion of Fig. 10 7 and Fig. 9 shows the ordinary flat head 12 of pivot 12'.

It will be seen that by pressing the tension device 4 at each side of the parts of the 15 adjustably movable cover structures, the said cover structures will collapse by moving the outer bars 26 toward the other end bars 18 and 11, thereby leaving the leaves free to be used or examined or searched on both of their faces.

20 The bar 26 is preferably made with a sloping surface 27 and rounded on its edges 28 to prevent cutting the leaves as they are folded back over said bar.

It may be desirable to cover the 25 adjustable parts of the movable cover structures with some suitable flexible material, or an accordion plaited material, such as made from cloth, paper, rubber, leather, fiber, vulcanized fiber, etc., but it is not thought necessary to illustrate this in the drawings.

It will be seen that the tension device 4 is 30 adjustable and movable with the movable members of the cover structures.

I do not care to limit myself to any particular construction of either movable cover structures; or to any particular form of 35 adjustably movable cover structures; or the materials of which they may be made, metal or not.

40 Having described my invention, what I claim is,—

1. A binder for leaves or the like comprising a binding means, means for securing the binding means to the leaves, and a collapsible cover structure secured at one end to the binding means in alinement with said binding means and adapted to be contracted in its original position to give access to the leaves and capable of being expanded to fit 50 the leaves.

2. A binder for leaves or the like, comprising means for binding the leaves, and opposing cover structures capable of being moved across the face of the leaves.

55 3. A binder for leaves or the like comprising clamping bars, binding posts detachably securing said bars in clamping position and a collapsible cover structure secured at one end to the bars in alinement 60 with them and adapted to be contracted in its original position to give access to the leaves as well as to be expanded to fit the leaves.

4. A binder for leaves or the like com-

prising clamping bars, binding posts detachably securing said bars in clamping position and for impaling the leaves, a collapsible cover structure secured at one end to and in alinement with said bars and adapted to be contracted and expanded, and tension devices connecting the free ends of said cover structures.

5. A binder for leaves or the like comprising clamping bars, binding posts detachably securing said bars in clamping position and a collapsible lazy tongs cover structure secured to said bars in alinement with them and adapted to be contracted or expanded.

6. A binder for leaves or the like, comprising means for binding the leaves and opposing cover structures capable of being moved across the face of the leaves with a tension device for jointly compressing the cover structures.

7. A binder for leaves or the like, comprising means for impaling the leaves and opposing cover structures capable of being moved across the face of the leaves.

8. A binder for leaves or the like, comprising means for binding the leaves, and opposing cover structures capable of being moved across the face of the leaves with means for securing the cover structures over the leaves.

9. A binder for leaves or the like, comprising means for binding the leaves and opposing cover structures capable of being moved across the face of the leaves with means for simultaneously moving said cover structures.

10. A binder for leaves or the like, comprising means for binding the leaves and a cover structure capable of being moved across the face of the leaves with a tension device simultaneously movable with said cover structure.

11. A binder for leaves or the like, comprising means for binding the leaves, and a cover structure capable of being moved across the face of the leaves for covering the leaves when closed and a detachable tension device for holding said cover structure to the leaves.

12. A binder for leaves or the like, comprising means for binding the leaves and jointly cover structures capable of being moved across the face of the leaves for covering the leaves when closed and a detachable tension device for jointly compressing the cover structures.

To which I affix my signature in the presence of two witnesses this 2nd day of January, nineteen hundred and seventeen.

ALBERT ROSENBERG.
